Primary Examiner — Clare Ann Gannon(74) *Attorney, Agent, or Firm* — Hinckley, Allen & Snyder, LLP; Stephen Holmes(57) **CLAIM**

The ornamental design for an articulated surface door mat, as shown and described.

DESCRIPTION

FIG. 1 is a front perspective view of an articulated surface door mat, showing my new design;

FIG. 2 is a front view thereof, the rear view being the same;

FIG. 3 is a left view thereof, the right view being the same;

FIG. 4 is a top view thereof;

FIG. 5 is a front perspective view thereof, shown in a position of use with environmental graphics;

FIG. 6 is a rear perspective view thereof, shown in a position of use with environmental graphics; and,

FIG. 7 is a top view thereof, shown in a position of use with environmental graphics.

The subject matter depicted in dotted lines in FIGS. 5, 6 and 7 is environment that forms no part of the claimed design.

1 Claim, 6 Drawing Sheets(56)
